Primary Examiner — Cynthia Ramirez*Assistant Examiner* — Jeremy S. Swartz(74) *Attorney, Agent, or Firm* — Bold IP, PLLC;
Christopher Mayle(57) **CLAIM**

The ornamental design for a ski rack, as shown as shown and described.

DESCRIPTION

FIG. 1 is a top perspective view of a ski rack in accordance with the present invention;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is another perspective view of a ski rack shown in use.

The broken lines in FIG. 8 depict environment and form no part of the claimed design.

1 Claim, 5 Drawing Sheets
